MERCURY SWITCH

Hugo Carl Rau, Bloomfield, N. J., assignor to
Westinghouse Lamp Company, a corporation
of Pennsylvania

Application March 13, 1931, Serial No. 522,200

6 Claims. (Cl 200—152)

This invention relates to mercury switch devices and relates more particularly to devices of the tilting type in which a pair of electrodes are arranged within a sealed container in which a movable body of mercury operates to make and break electrical connections between electrodes.

It has been common to provide mercury switches of the above character and such switches were usually divided into two classes, 10 the horizontal tilting type and the vertical tilting type. By horizontal tilting type is meant that the switch is normally disposed with its longitudinal axis substantially horizontal and the tilting of the device about a point intermediate its ends causes the mercury body to flow in one direction to make the circuit and in the opposite direction to break the circuit. The vertical type is operated with the longitudinal axis of the device in a substantially vertical position and the mercury is moved to make and break the circuit by a tilting of the device about a point along the vertical axis.

A mercury switch of the horizontal type is shown in Patent No. 1,762,213 issued to George F. Callahan on June 10, 1930 and a switch of the vertical type is shown in a copending application Serial No. 472,222 filed August 1, 1930 by C. V. Iredell and assigned to the assignee of the present invention.

30 Mercury switches are employed in various types of equipment and owing to the physical construction of such equipment as well as the use to which it is to be put, it is necessary to provide both horizontal and vertical type constructions of switches since a horizontal type might be applicable in one apparatus whereas another apparatus may be constructed so as to only provide room for a vertically operable switch.

40 Furthermore it is the usual practice to provide a vertical operable switch to give the more rapid make and break operation.

It is an object of the present invention to provide a mercury switch so constructed and arranged that it may be operable either in a horizontal or a vertical position.

Another object of the invention is to provide a mercury switch with an internal insulator element so proportioned and formed as to control 50 the flow of mercury during vertical or horizontal operation.

Another object of the invention is to provide a mercury switch construction which may be manufactured in an economic and expeditious 55 manner.

Other objects and advantages of the invention will be apparent from the following description together with the accompanying drawing, in which

Fig. 1 is a vertical cross sectional view of a 60 mercury switch constructed in accordance with the present invention;

Fig. 2 is a view taken on line II—II in Fig. 1; Fig. 3 is a view similar to Fig. 1 but showing 65 the device in a tilted position;

Fig. 4 is a view taken on line IV—IV in Fig. 3;

Fig. 5 is a view similar to Fig. 4 but showing 70 the switch tilted with the mercury pool divided to break electrical connection;

Fig. 6 is a sectional view of the switch shown 70 in position for horizontal tilting;

Fig. 7 is a view taken on line VII—VII in Fig. 6;

Fig. 8 is a view similar to Fig. 6 but shows the 75 switch tilted in an opposite direction;

Fig. 9 is a view taken on line IX—IX in Fig. 8;

Fig. 10 is a perspective view of the refractory or insulating elements showing the upper side in which a pocket is formed which element is employed for controlling the flow of mercury from 80 one electrode to the other, and

Fig. 11 is a perspective view of the insulative element shown in Fig. 10 viewed from the opposite end.

A mercury switch device constructed in accordance with the present invention may comprise a glass bulb or envelope 10. As illustrated this envelope is preferably of elongated cylindrical form and one end is sealed by compressed portion 11 in which are sealed leading in wires 85 or conductors 12 and 13. The compressed portion 11 includes an exhaust tube 11' through which the bulb may be exhausted in the usual manner. The exhaust tube may be employed for admitting a quantity of mercury 17 to the bulb. 90 The leading in wires 12 and 13 extend into the bulb and terminate in electrodes 14 and 15 respectively. The free or exposed ends of the electrodes are disposed adjacent to one end of the bulb.

A deposit of mercury within the bulb would obviously result in an electrical connection between the electrodes. For the purpose of controlling the flow of mercury the bulb is provided with an insulative member 18 of a refractory material such for example as Lavite, a commercial product comprised in major part of finely pulverized lava rock which is compacted under great pressure to coherent form.

This material may be either pressed to the de- 110

sired form or machined to any given configuration and subsequently fired at elevated temperatures to render it strong and refractory.

It is obvious, however, that other suitable insulative or refractory materials may be molded or otherwise shaped for use as the member or element 18. The mercury controlled element may be formed with a portion of its surface cylindrical to provide a face 19 of such diameter as to fit the interior wall of the bulb. This element 18 as shown more clearly in Figs. 10 and 11 may be provided with a platform 21 having a cavity 22 and a surrounding wall 23 extending upwardly from the platform and partly enclosing the perimeter of the cavity 22.

When such a device is used for vertical operation as shown in Fig. 1 the cavity 22 contains a filling of mercury constituting what may be termed a stationary pool 24 and the lower end 20 of the electrode 14 is disposed in the cavity 22 and consequently in contact with the mercury pool 24. The remaining portion 25 of the mercury which may be considered as the movable portion, surrounds the lower end of the electrode 15 which is provided with an extension 26. This extension is provided to make the switch operable when in a horizontal position as will presently be described.

The switch as shown in Fig. 1, that is, when 30 it is employed to operate in a vertical position, may be assumed to rock about pivot point 27. When the switch is in an exact vertical position a lip 28 of the cavity 22 serves to act as an obstruction or barrier to separate the two bodies 35 of mercury and thus the electrodes are electrically disconnected. When the switch is tilted, as shown in Fig. 3 the mercury flows across the lip 28 connecting the two bodies of mercury and thus electrically connecting the electrodes.

40 The position of the two bodies of mercury separated by the lip 28 is clearly shown in Fig. 2 while the connected bodies of mercury are clearly shown in Fig. 4 so that it will be readily appreciated that a slight tilting of the device in one 45 direction serves to cause the lip 28 to divide the mercury into two separate bodies and a tipping in the opposite direction causes a division of the bodies of mercury and a break in the electrical connection between the electrodes. The switch 50 as shown is constructed that when in an exact vertical position it is in an inoperative position insofar as the flow of current between the electrodes is concerned, since the lip 28 which constitutes a barrier serves to electrically separate 55 the mercury bodies.

The present mercury switch device may as shown in Figs. 6, 7, 8 and 9 be operated in a substantially horizontal position. The refractory element 18 is so formed as to provide a 60 ledge 29 and a rounded surface 31, which latter is shaped to conform with the surface of the bulb and the refractory element 18 is so disposed with the ledge 29 as contiguous with the wall at the lower end of the bulb so that the 65 ledge in conjunction with the bulb wall 32 provides a pocket to receive what may be termed a stationary pool of mercury 34.

The extension 26 extends along the ledge 29 and is thus in contact with the mercury pool 34. 70 The remaining portion of the mercury which may be termed a movable body 35 is separated from the stationary pool by a barrier or wall 33 as when the device is in position as shown in Fig. 8, that is, tilted about a pivot point 36 and disposed at a slight angle above a horizontal line. 75

When the device is tilted as shown in Fig. 6 to a position below a horizontal line, the movable body of mercury flows across the barrier 33 as shown in Fig. 7, thus connects the two bodies of mercury and provides electrical connection 80 between the electrodes.

From the foregoing it will be evident that by reason of the novel construction of the refractory element 18 a mercury switch device may be provided which is operable in a substantial vertical position and which without any alteration or adjustments may be converted to a switch 85 operable in a horizontal position.

Although the present switch is shown and described as having electrodes normally in contact with separate bodies of mercury it is to be understood that a switch device may be made wherein a single body of mercury moves back and forth to make and break a circuit and that 90 is not essential to provide a stationary pool in contact with one of the electrodes.

The advantages derived from the present invention are obvious, since whereas it was heretofore necessary to manufacture two types of switches for horizontal or vertical operation, it 100 is possible by reason of the present invention and with substantially the same cost of either type of switch, to provide one which will answer the requirements under a variety of conditions, thus not only reducing manufacturing costs but 105 affording a greater range of surface and extending the usefulness of the device.

Although a preferred embodiment of the invention is shown and described herein, it is to be understood that modifications may be made 110 therein without departing from the spirit and scope of the invention as set forth in the appended claims.

What is claimed is:

1. A mercury switch device comprising a tubular sealed envelope, a body of mercury in said envelope, a refractory element having a surface of cylindrical form to fit one portion of the inner wall of said envelope and a planar wall spaced from an opposite portion of said envelope, 120 said element having a pocket with the open end disposed in a plane transverse to the longitudinal axis of the envelope to hold a portion of said mercury during vertical operation of the device, another surface of said element being 125 spaced from the wall of said envelope to provide another pocket to hold a portion of said mercury during horizontal operation of the device, and conductive members extending into 130 said pockets.

2. A mercury switch device comprising a tubular sealed envelope, a refractory element having one surface arranged to fit a portion of the interior surface of the envelope and so proportioned as to provide a space between another 135 surface thereof and an opposite portion of the interior surface of the envelope, a relatively large body of mercury, said element having a pocket to hold another body of mercury when said body of mercury is disposed in said space, 140 said bodies being divided by a wall of said pocket and disposed substantially on opposite sides of the longitudinal axis of said envelope, and conductive members extending into said pocket and said space.

3. A mercury switch device comprising a sealed envelope, a refractory element having one surface arranged to fit a portion of the interior surface of the envelope and so proportioned as to provide a space between another surface 145

thereof and an opposite portion of the interior surface of the envelope, said element having a pocket disposed at one side of the longitudinal axis of said envelope to hold a portion of said mercury when the main body of mercury is disposed in said space during vertical operation of the device, a ledge on said element to cooperate with a portion of the wall of said envelope to provide a pocket to hold a pool of mercury during horizontal operation of the device and conductive members extending into said pocket and the remaining portion of said mercury.

4. A mercury switch device comprising a tubular sealed envelope, a pair of conductive members sealed in the wall at one end of said envelope, a refractory element disposed within and at the other end of said envelope, said element being formed with a surface to engage with a portion of the wall of said envelope and with another surface in spaced relation to the wall of said envelope, a body of mercury in said envelope disposed between said surface and wall during operation of said device, said element having a pocket with the open end in a plane transverse to the longitudinal axis of the envelope to separate a pool of mercury from said body, said conductive members extending into said pool and body.

5. A mercury switch device comprising a tubular sealed envelope, a refractory element having a pocket disposed with the mouth thereof in a plane transverse to the longitudinal axis of the envelope to receive a pool of mercury during vertical operation, said element being spaced from one wall of the envelope to provide space for a body of mercury during vertical operation of the device and spaced from another wall of the envelope to provide a pocket for a pool of mercury during horizontal operation of the device.

6. A mercury switch device comprising a sealed envelope, a refractory element, one side of said element being disposed in close proximity to a wall of said envelope and the other side of said element being spaced from said wall to provide a recess to hold a body of mercury, a wall extending from said element, said wall having a pocket to hold a pool of mercury when the device is operated with its longitudinal axis substantially vertical, said wall serving in conjunction with a wall of said envelope to provide a pocket for a pool of mercury during horizontal operation of said device.
